UNITED STATES PATENT OFFICE

ANDERS JOSEF JONSSON, OF LINKOPING, SWEDEN

MACHINE FOR MAKING CAPS

Application filed December 6, 1928, Serial No. 324,193, and in Sweden November 11, 1927.

This invention refers to means for crisp-
ing or crimping the tongue in metallic caps
for bottles in which the tongue extends from
the rim of the cap.

5 The invention is illustrated in the accom-
panying drawing, where

Figure 1 is a perspective view of a cap ac-
cording to the invention;

10 Figure 2 is a vertical section of a stamping
tool for performing the crisp-
ing, the said
tool being here shown combined with a tool
already known for inserting packing in the
finished cap;

15 Figure 3 is a plan view of the stamping
matrix;

Figure 4 shows the stamp from the under
side; and

20 Figure 5 shows the combination used in
such capping machines in which the cap is
pneumatically conveyed from tool to tool.

25 In Figure 1 the cap tongue *a* is crimped
or crinkled. The crimping may be effected
by different tools but it is most suitable to
use a stamping tool, that is to say, a stamp
with matrix. According to the invention,
30 the said two parts are preferably combined
with a tool by which the cap is treated, for
instance, with the tool for inserting packing
in the cap, as shown in the drawing.

35 The construction of the said tool being al-
ready known the drawing only shows so much
of it as is necessary for rendering the inven-
tion clear. The main parts of the said tool
are the reciprocating shell or upper stamp 1

40 movable up and down, and the lower stamp
or rod 2 also movable up and down in a sleeve
3 of the fixed bed or machine table 4. The
stamp 1 goes down to the said sleeve just after
the cap advances under the stamp, whereby

45 the cap becomes located in the hollow or fe-
male section of the stamp. Simultaneously
a cork-leaf laid over the rod 2 is pushed into
the cap by the rod. The cap is then pushed
out from the stamp 1 by a small rod 5. Fig-

50 ure 2 shows a cap by dot-and-dash lines on
its way in under the stamp 1. The parts
mentioned above are already known and, con-
sequently, the construction and the operating
manner of same need not be described more
closely.

According to the invention the stamp 1
is now shaped as a crimping stamp also and
has at its one side an enlargement or swell
7, the lower surface of which is crispy and
forms the working surface or male section
cooperating with a corresponding surface or
female section of the matrix 8. The cap will
be located under the stamp in such a manner
as to allow the tongue to be placed between
the said surfaces, the crisp-
ing being then ef-
fected at the same time as the packing is in-
serted, that is to say, these two operations
are made in a single step.

55 In the machine shown in Figure 5 the
crimping stamp is combined in the same
manner with the tool for inserting the pack-
ing. In this machine the cap is moved from
a stamping and bending tool located at *b*
where the cap is made, to the tool 1, 2 (Figure
60 5 only shows the lower stamp 2) and
further to rotating nozzles located at *c* where
the capping is effected. The movement of
the cap is effected by means of an air current
from a nozzle 13 in a tube for pressure air.
65 10 is a conveyer for feeding cork-leaves to
the tool. 9 is one half of a channel in which
the cap is conveyed from tool to tool. Con-
cerning the suitable position of the cap for
being inserted in the nozzles the cap tongue
70 *a* may be directed backwards in relation to
the conveying direction and the crimped sur-
faces may of course be located on the side
not facing the nozzles. In order that the
cap may not stick when it is to be moved by
75 the air current from the said stamps 1, 2, the
working surface of the lower stamp 2 may,
on this occasion, be on a level with the work-
ing surface of the crimping matrix 8, the
stamp being maintained in this position until
80 the cap has passed over it.

85 Having now described my invention, what
I claim as new and desire to secure by Letters
Patent is:

1. In a device of the character described,
a packing inserting and crimping tool for
90 tongued caps, comprising a reciprocating
shell provided with the female section of the
packing inserting tool and the male section
of the crimper, a fixed bed having an open-
ing registering with the female section of the
95 100

packing inserting tool and the female section of the crimper disposed marginally of the opening, and a lower stamp forming the male section of the packing member reciprocally mounted in the opening.

5 2. A device as claimed in claim 1, in which the crimping portion of the tool is formed by an enlargement arranged on one side of the tool.

10 3. A device as claimed in claim 1, in which the female section of the crimper is disposed on an elevation substantially the same as that reached by the working face of the lower stamp in its uppermost position.

15 In witness whereof, I have hereunto signed my name.

ANDERS JOSEF JONSSON.
